UNITED STATES PATENT OFFICE.

LAWRENCE D. SIBERT, OF JACKSONVILLE, ILLINOIS, ASSIGNOR, BY DIRECT AND MESNE ASSIGNMENTS, TO NEW METHOD BOOK BINDERY, (INC.), A CORPORATION OF ILLINOIS.

BOOKBINDING.

1,332,767.

Specification of Letters Patent.

Patented Mar. 2, 1920.

Application filed April 16, 1919. Serial No. 290,494.

To all whom it may concern:

Be it known that I, LAWRENCE D. SIBERT, a citizen of the United States, residing at Jacksonville, in the county of Morgan and State of Illinois, have invented certain new and useful Improvements in Bookbinding, of which the following is a specification.

This invention comprehends improvements in bookbinding and the general object 10 of the invention is to provide a novel binding between the book sections, and the cover board so as to materially strengthen the construction and reduce the strain in the opening and the closing operations of the book.

15 The primary object of the invention is binding of the above stated character, which is durable and efficient in use and one principally designed for use in connection with a whip-stitched book, whereby the units or 20 sections constituting the body of the book may be firmly united with the cover.

25 A still further object of the invention is a device of the above stated character, wherein use is made of a strip of material pasted or otherwise suitably secured to the blank with one edge thereof lapping the fold of the blank to facilitate the stitching thereto of the outermost units or sections of the book body.

30 Another object of the invention aims in providing a pair of flaps adapted to be stitched together with the strip and certain sections of the book body.

With such and other objects in view, the 35 invention comprises various novel features of construction and arrangement of parts which will hereinafter be set forth with particularity in the specification and the appended claims.

40 In the accompanying drawings, which illustrate one embodiment of the invention and wherein similar characters of reference indicate corresponding parts in all the views:—

45 Figure 1 is a perspective view of a book, with the cover secured thereto.

Fig. 2 is a section taken on line 2—2 of Fig. 1.

50 Figs. 3 and 4 are detail perspective views of the binding elements removed.

Fig. 5 is a side elevation of one fold attached to one section of the book.

Fig. 6 is a view similar to Fig. 5, illustrating the reverse or opposite side.

Fig. 7 is a view of the fold in open position, and

Fig. 8 is a section taken on line 8—8 of Fig. 1.

In practice, whip-stitched books have been found to be advantageous, but difficulty is experienced in retaining the cover boards on the books, therefore the principal object sought is a binding for a whip-stitched book which may be firmly united or secured in its covers.

To this end, and in order that a clear understanding of the invention may be had, the book body, is here denoted by the character A embodying a series of outer and inner sections or signatures B and C respectively united or connected to one another by a whip-stitch D.

Pasted or otherwise suitably secured to and lengthwise of the outside of a fold 6, which is the inside of the book lining, is a 75 binding strip 7, preferably made of buckram, but if desired it may be constructed of any other suitable material, and this strip is of such width as to leave extended beyond the back edge 9 of the fold an extension 80 8. The extension 8 is lapped around said edge of the fold and initially pasted to the outside of the first or last section of the book body 10, as the case may be, so that the back edge of the fold is even with the 85 back of the section. The extensions are then stitched to either of the outermost sections of the book to provide a flexible hinge for the cover boards 11. The character 12, denotes flaps, constructed preferably of 90 buckram, or like material, and these flaps are for ease in handling, pasted or fastened in pairs to the inner side of each of the outermost sections, as indicated at 13, with one flap arranged adjacent the top edge of 95 the leaves and the other disposed in close proximity to the bottom of the leaves.

The opposite end 14 of each flap is bent around the back edge of the said book section and stitched to the inside of the cover 100 board beneath the lining 15 and under the strip 7. Previous to the operation of connecting the flaps with the cover board and the assembling of the body of the book composed of a series of sections, I punch all the 105 sections, punching with the outer sections the extensions 8 of strips 7 and the two flaps where pasted on the book sections at 13,

then whip-stitch onto the first section, the second section, and so on until all the sections C are united. In stitching the first and last sections the stitches pass through the flaps at 13 and the extensions 8. Thereafter the book is prepared for the cover boards, the flaps are pasted to the cover boards and wire stitched thereto as shown at 16; the book is then prepared for lining and the inner side of the lining is pasted to the cover boards, leaving 17 of fold 6 as the fly leaf. The cloth covering of the cover boards is put on in preparing the book for the lining.

I desire to have it understood that even though the foregoing operation of binding books is principally designed for rebinding old books, magazines, newspapers and periodicals, the same may be used in binding books of any character, and provides a substantial, durable and efficient binder sufficient for extended use of books as in public or circulating libraries; and at the same time insures a greater flexibility between the body of the book and the cover. This construction further allows the cover to open more freely than usual, so that the strain between the first and second sections is reduced to a minimum and there is less danger of the cover breaking away.

From the foregoing description taken in connection with the accompanying drawings, the advantages of the construction and method of operation will be readily understood, by those skilled in the art to which the invention appertains, and while I have described the principle of operation, together with the article which I now consider to be the best embodiment thereof, I desire to have it understood that the article shown is merely illustrative and that such changes may be made when desired as fall within the scope of the appended claims.

Having thus described the invention what I claim as new, is:—

1. A book comprising a series of sections, 45 a cover therefor composed of a back and side boards, a lining between each of said side boards and the adjacent section, a strip secured to the outside of said lining, a pair of flaps stitched at one end between a pair 50 of sections and through a section to one edge of the strip, the opposite end of each flap lying beneath the strip and rigidly connected with the cover boards.

2. A book comprising a series of sections, 55 a cover therefor composed of a back and side boards, a lining between each of said side boards and the adjacent section, a strip secured to the outside of said lining with a portion thereof extending around to the inner side of the lining, flaps between two sections, a single row of stitching connecting the extended edge of said strip and one end of each of said flaps to the sections of said book, and means for connecting the 60 65 cover boards to said flaps.

3. A book comprising a series of sections, a cover therefor composed of a back and side boards, a lining between each of said side boards and the adjacent section, a strip 70 secured to the outside of said lining with a portion thereof extending around to the inside of said lining, flaps between two sections, a single row of stitching connecting the extended edge of said strip and one end 75 of each of said flaps to a section of said book, the opposite end of said flaps being connected to the cover.

In testimony whereof I affix my signature.

LAWRENCE D. SIBERT.
